UNITED STATES PATENT OFFICE.

DANIEL W. YOUNG, JR., OF CHICAGO, ILLINOIS.

SELF-HEATING SAD-IRON.

1,092,196.

Specification of Letters Patent.

Patented Apr. 7, 1914.

Application filed May 31, 1913. Serial No. 770,984.

To all whom it may concern:

Be it known that I, DANIEL W. YOUNG, Jr., a citizen of the United States, and a resident of the city of Chicago, county of Cook, and State of Illinois, have invented 5 certain new and useful Improvements in Self-Heating Sad-Irons, of which the following is a specification.

My invention relates to improvements in 10 self heating sad-irons and has particular reference to that class thereof designed for use where kerosene is used as the fuel.

The object of my invention is the production 15 of a sad-iron as mentioned which will be of durable and economical construction and efficient in use.

Other objects will appear hereinafter.

The invention consists in the combinations 20 and arrangements of parts hereinafter described and claimed.

The invention will be best understood by reference to the accompanying drawings forming a part of this specification, and in which—

25 Figure 1 is a central vertical section of a sad-iron embodying my invention, Fig. 2 is a horizontal section taken on substantially line $w-w$ of Fig. 1, Fig. 3 is a vertical transverse section taken on substantially line 30 $x-x$ of Fig. 1, Fig. 4 is an enlarged vertical section taken on substantially line $y-y$ of Fig. 2, Fig. 5 is an enlarged detail section taken on line $z-z$ of Fig. 2, Fig. 6 is an enlarged bottom plan view of the cover of the 35 body of the iron, Fig. 7 is an enlarged front elevation of a fitting used in the connection of the drain pipe of the fuel tank with the generator of the iron, and Fig. 8 is a perspective view of the outer end of said drain 40 pipe of the fuel tank which engages with the fitting shown in Fig. 7.

The preferred form of construction as illustrated in the drawings comprises a hollow body 1 of usual form, open at its upper 45 side. Arranged within the body 1 in superposed relation are the generator 2 and the burner 3, the latter being of course arranged below the former. The burner 3 is supported in operative position by means of a 50 depending arm 4 provided at the inner end of the generator 2, the arm 4 embracing the lower end of a substantially U-shaped pipe section 5 which serves in the capacity of a mixing chamber, one end of the burner 3 being threaded into the corresponding end 55 of the member 5, the latter in turn being

secured to the supporting arm 4 by means of a set screw 5'. The upper end of the member 5 is spaced from the discharging orifice of the generator 2 in order to effect a thorough mixing of the gas issuing from said orifice before reaching the burner 3.

The outer end of the generator 2 is provided with an enlargement 6, rectangular in form, which snugly fits a slot 7 of corresponding form provided in the upper edge of the rear wall of the iron. The lateral edges of the enlargement 6 are of channel form, as shown, for embracing the adjacent edges of said slot whereby said generator 65 and hence the burner and mixing chamber are supported in operative position. The lower edge of the enlargement 6 is provided with depending pointed projections 8 which engage notches 9 provided in the bottom of 70 the slot 7, this construction serving to securely hold said enlargement 6 in position in the slot 7 preventing free movement.

The burner 3 is provided at its under and upper sides with spaced transversely extending slits 10 and 11 respectively through which the fuel escapes for combustion. The openings 10 are larger than the openings 11 in order to permit of escape of a greater amount of gas to support a primary flame 80 for the heating of the bottom of the iron larger than that which will be supported at the upper side of the burner for heating the generator 2 in the generation of the liquid fuel into gas. The upper side of the bottom 85 of the iron body is hollowed out slightly to conform substantially with the formation of the burner, and projections 12' are provided at either side of the burner, arranged in alinement with the openings 10 thereof 90 which serve as obstructions to prevent spreading of the jets into engagement with the lateral walls of the iron. Without the provision of obstructions as mentioned the flame at the under side of the burner spreads 95 over the entire bottom of the iron and impinges against the lateral walls of the body of the iron, considerable fuel being thus wasted in the heating of said walls. With the present construction, the flame will be 100 confined to the bottom or operative portion of the iron body and thus economy in fuel effected.

Arranged at the rearward end of the iron at one side thereof is the fuel tank 12 provided with a filling plug 13 of ordinary construction. Leading from the bottom of the

tank 12 is the fuel outlet pipe 14 the outer or lower end of which is connected with a nipple 15 formed at the rearward end of the generator 2. Said end of said outlet pipe is connected with the nipple 15 through the medium of a fitting 16, one end of which is threaded into said nipple, the end of said outlet pipe loosely fitting in said fitting as clearly shown in Fig. 4. At the extremity 10 of the pipe 14 are provided diametric ears or lugs 17 which engage recesses 17' provided in the member 16, which serve to lock the pipe 14 against relative rotary movement in said member 16 and hence to maintain the tank 12 in upright position. Snugly fitting the pipe 14 adjacent the end thereof is a tapering collar 18 adapted to engage a seat 19 formed in the member 16. Loosely mounted upon said pipe 14 is a screw cap 20 adapted for threaded engagement with the outer end of fitting 16. The cap 20 engages against the outer end of the collar 18 serving to force the latter into secure engagement with the seat 19, the latter in turn pressing said collar into close engagement with the pipe 14, whereby an absolutely tight joint is effected without the use of packing such as is now generally used. The bottom of the cap 20 which engages against 25 the outer end of collar 18 is beveled, as shown, in order to also press said end into close engagement with the pipe 14, when said cap is threaded into the member 16 to operative position.

30 The flow of fuel to the generator is governed by a valve 21 which is threaded in the outer end of said generator, an exteriorly positioned hand wheel 22 being provided for operating said valve. The inner end of said valve is adapted for engagement with a seat 23, as clearly shown in Figs. 1 and 2, the same being adapted, when in engagement with said seat, to shut off the supply of fuel to the generator.

35 Secured to the inner end of the valve 21 and extending coaxially therewith is a rod or stem 24 hexagonal in form which snugly fits the passage 25 through the generator. With this arrangement it will be seen that 40 the passage through the generator will be divided into a plurality of smaller passages segmental in cross-section which register with the faces or sides of the member 24, it being clear that the edges of said member 24 engaging against the sides of the passage 25 result in this division. The formation of a plurality of narrow passages through the generator, results in the division of the fuel introduced into the generator into as 45 many thin streams which of course may be more readily heated than one solid stream, thereby facilitating the generating process. This arrangement is further of advantage in that the passage through the generator, 50 with this construction, will be continually

cleaned through operation or rotation of the valve. Upon rotation of the valve the edges of the member 24 will rub against the sides of the passage 25 and thereby effect dislodging of any particles or carbon which might otherwise clog said passage, the clogging of the passage through the generator of a sad-iron of this nature, through carbonization, being one of the greatest objections to this kind of an iron. With the present construction this objection will be overcome and without any extra effort on the part of the operator, the cleaning being done simultaneously with the operation of the valve. The member 24 may be cleaned occasionally by removing the valve 21, said member 24 being carried thereby. The member 24 is of such a length as to project through the discharge orifice of the generator, when the valve is in closed position 55 in order to dislodge any foreign matter which might clog said orifice. The outer end of said member 24 however does not seat against the contracted end of the passage 25, the latter always remaining open so that upon closing of the valve 21 any fuel which is left in said passage may escape therefrom.

The upper side of the body 1 is closed by a cover 26 which is provided with a suitable handle 27. Said cover is releasably locked to the body 1, at its front end, by means of fingers 28 provided at the under side of said cover which engage notches 29 provided in the upper edges of the lateral walls of said 60 body. A depending lug 30 provided at the front end of the cover 26 is adapted to fit snugly in the vertex of the iron between the lateral walls thereof to prevent relative lateral movement of the cover when in operative position. The rearward end of said cover is secured in position by means of a thumb screw 31 which is threaded in one of the lateral walls of the body 1, the head of said screw engaging a notch 32 provided in 65 the adjacent end of the cover. The edge of the notch 32 and the base portion of the head of screw 31 are beveled so as to insure a snug engagement and conduce to a secure fastening of the cover to the body. A lug 33 provided at the rearward end of the cover is adapted to engage against the rear wall of the body 1 to prevent movement of the cover in one direction, lateral movement thereof in the opposite direction being of course prevented by screw 31. With this arrangement 70 it will be seen that detachment of the cover may be effected upon retraction of the screw 31.

Provided at the under side of the cover 26 75 is a transversely arched deflector plate 34 which is spaced slightly from said cover as clearly shown in Figs. 1 and 3. The plate 34 serves to deflect the heated gases arising from the burner through lateral ventilation 80

openings which are provided at the opposite sides of the iron by cutting away the upper edge portions of the lateral walls of the body 1, thereby serving to prevent heating of the handle 27. By spacing the deflector plate 34 from the cover, cool air may circulate between said parts from one side of the iron to the other and thus serve in a sense to insulate the handle from the heated portion of 10 the iron.

A sad-iron of the construction set forth will be found effectual in use, the same may be readily cleaned and may be manufactured at a low cost.

15 While I have illustrated and described the preferred form of construction for carrying my invention into effect, this is capable of variation and modification without departing from the spirit of the invention. I, 20 therefore, do not wish to be limited to the precise details of construction set forth, but desire to avail myself of such variations and modifications as come within the scope of the appended claims.

25 Having described my invention what I claim as new and desire to secure by Letters Patent is:

1. In a self heating sad iron, a hollow body having a rectangular recess in its rear wall with smaller recesses extending downwardly from the lower side of said recess; burner mechanism in said hollow body and extending through said rectangular recess; an enlargement on said burner mechanism 30 conforming with and fitted in said rectangular recess; and projections on said enlargement fitting in the recesses at the lower side of said rectangular recess, substantially as 35 described.

2. In a self heating sad-iron, a hollow body; a burner and a generator arranged in said body in superposed relation; an enlargement at one end of said generator engaging a slot provided in the rear wall of 40 said body for supporting said generator in 45 operative position; pointed ears at the under side of said enlargement engaging recesses in the bottom of said slot for locking said members against relative movement; and a fuel supply communicating with said generator, 50 substantially as described.

3. In a self-heating sad iron, a hollow body; a burner and a generator arranged in said body in superposed relation, the inner ends of said burner and generator being in 55 communication; a fuel supply communicating with the outer end of said generator, said burner having transversely extending fuel discharge openings at the upper and under sides thereof; and obstructions upon 60 the under side of the bottom of said body in alinement with said openings at either side thereof, substantially as described.

4. In a self heating sad iron, a hollow body; a burner in said hollow body having 65 transversely extending fuel openings in its upper and lower sides; and obstructions on the upper side of the bottom of said body in alinement with said openings at either side 70 thereof, substantially as described.

In testimony whereof I have signed my name to this specification in the presence of two subscribing witnesses.

DANIEL W. YOUNG, JR.
